Primary Examiner — Bridget L Eland*(74) Attorney, Agent, or Firm* — Sheridan Ross P.C.(57) **CLAIM**

The ornamental design for an intervertebral surgical tool, as shown and described.

DESCRIPTION

FIG. 1 is a front perspective view of the intervertebral surgical tool;

FIG. 2 is a top plan view thereof;

FIG. 3 is a front elevation view thereof;

FIG. 4 is a right elevation view thereof;

FIG. 5 is a left elevation view thereof;

FIG. 6 is a rear elevation view thereof;

FIG. 7 is a bottom plan view thereof;

FIG. 8 is a front perspective view of the intervertebral surgical tool shown in an alternate environment;

FIG. 9 is a top plan view thereof;

FIG. 10 is a front elevation view thereof;

FIG. 11 is a right elevation view thereof;

FIG. 12 is a left elevation view thereof;

FIG. 13 is a rear elevation view thereof; and,

FIG. 14 is a bottom plan view thereof.

The broken lines showing an intervertebral surgical tool are included for the purpose of illustrating environment and form no part of the claimed design.
